UNITED STATES PATENT OFFICE.

WILLIAM C. HUSS, OF CINCINNATI, OHIO.

DESIGN FOR A BAR-FIXTURE.

No. 37,610.

Specification for Design.

Patented Oct. 31, 1905.

Application filed May 19, 1905, Serial No. 261,269. Term of patent 7 years.

To all whom it may concern:

Be it known that I, WILLIAM C. HUSS, a citizen of the United States of America, and a resident of Cincinnati, county of Hamilton, State of Ohio, have invented a certain new, original, and ornamental Design for a Bar-Fixture, of which the following is a specification.

I claim—
The new original and ornamental design for a bar-fixture as shown.

WILLIAM C. HUSS.
